UNITED STATES PATENT OFFICE

2,692,503

PIPETTE

Harry G. Crecelius, Phoenix, Ariz., assignor to
 Owens-Illinois Glass Company, a corporation
 of Ohio

Application July 9, 1952, Serial No. 297,955

2 Claims. (Cl. 73—425.4)

1

This invention relates to pipettes and particularly to pipettes intended for use in bacteriology or serology.

In using pipettes in bacteriology or serology, it is customary to place a plug of cotton or other cellular material in the end of the pipette to prevent the passage of bacteria either from the mouth of the user to the liquid being handled, or from the liquid into the mouth of the user. This plug of cotton often becomes displaced in the pipette making its removal difficult, if not practically impossible. This occurs especially where one end of the pipette has a reduced diameter, as compared to the remainder of the pipette.

It is therefore an object of the invention to provide a pipette having a construction whereby this difficulty is obviated.

Other objects of the invention will appear hereinafter.

The accompanying drawing shows a fragmentary part-sectional elevational view of a pipette embodying my invention.

As shown in the drawing, the pipette 10 is of substantially uniform internal diameter and uniform wall thickness throughout. The pipette is made of glass or other suitable material. The pipette has one end 11 thereof tapered to form a dropper tip. The other end 12 is customarily referred to as the mouthpiece. As shown the pipette is formed with a constriction 13 near the mouthpiece thus separating the mouthpiece from the main body of the pipette.

The constriction 13 has a reduced internal diameter sufficient to prevent the displacement of a plug of cotton 15 or other cellular material downwardly into the pipette. The diameter of the constriction is not sufficient however to materially affect the capillary action of the pipette.

The pipette may also be provided with calibration marks 14 or other indicia.

The constriction 13 is preferably formed by heating the pipette in the localized region of the

2

intended constriction and applying a suitable tool to the external surface thereof. As shown in the drawing, this causes a change in both the external and internal diameters.

By this construction, a plug of cotton 15 placed in the mouthpiece of the pipette is prevented from being displaced downwardly into the pipette.

Modifications may be resorted to within the spirit and scope of the appended claims.

10 I claim:

1. A unitary pipette comprising a tube having one end thereof tapered to form a tip, said tube having a portion thereof between the tip and the other end and near and spaced from the other end restricted in such a manner that the interior diameter of the tube is reduced at said portion, the interior diameter above said portion toward the end of the tube being greater than the diameter of the restricted portion whereby a plug 15 of cellular material inserted in the end of the tube is prevented from being displaced downwardly in the tube beyond the restricted portion.

2. A unitary pipette comprising a tube having one end thereof tapered to form a tip, said tube having a portion thereof near and spaced from the other end restricted in such a manner that the interior diameter of the tube is reduced at said portion, the interior diameter of said tube above said restricted portion being greater than the diameter at said restricted portion, and a plug of cellular material inserted in the end of the tube above said restricted portion, said restricted portion preventing the downward displacement of said plug of cellular material into the tube.
